Primary Examiner — Darlington Ly(74) *Attorney, Agent, or Firm* — David A. Lowin(57) **CLAIM**

The ornamental design for a toy car, as shown and described.

DESCRIPTION

FIG. 1 is a right side elevational view of my invention; FIG. 2 is a front elevational view thereof;

FIG. 3 is a top plan view thereof;

FIG. 4 is a rear elevational view thereof; and,

FIG. 5 is a right front perspective view thereof.

The broken lines shown in the drawings illustrate portions of the toy car that form no part of the claimed design.
